CLAIM

The ornamental design for an earphone, as shown and described.

DESCRIPTION

FIG. 1 is a top, front, right perspective view of a right-side earphone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top, front, left perspective view of a left-side earphone showing an alternate embodiment of our new design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

(Continued)

The broken lines immediately adjacent to the shaded area define the bounds of the claimed design, and the broken lines are for illustrative purposes only; the broken lines form no part of the claimed design.

1 Claim, 14 Drawing Sheets
